LIFE SAVING DEVICE

Charles Herendeen, Chicago, Ill.

Application March 26, 1941, Serial No. 385,348

5 Claims. (Cl. 227—39)

The invention relates to life saving devices and has as an object the provision of a device to aid the escape of people from a burning building, a ship in distress, or the like.

It is an object of the invention to provide a flexible chute which may be attached to the structure from which escape is desired, and which will provide for safe delivery of persons sliding within the interior thereof even though passing through fire or water.

Further objects of the invention will appear from the following description when read in connection with the accompanying drawings showing an illustrative embodiment of the invention, and wherein:

Fig. 1 shows the device applied to a building in connection with a ladder;

Fig. 2 is a detail vertical section on an enlarged scale through a portion of the building at a window, and showing the upper end of the chute in full lines;

Fig. 3 is a detail plan view of the top only of the chute and a ladder;

Fig. 4 is a detail vertical section of the upper end of the chute;

Fig. 5 is a section through a windowsill and a detail of the chute as applied thereto without a ladder;

Fig. 6 is a detail side elevation of a form of conveyor rope and loops;

Fig. 7 is a plan view of the structure of Figure 5 omitting the building structure;

Fig. 8 is a detail side elevation of the delivery end of the chute showing the handles attached thereto;

Fig. 9 is an end elevation of the structure of Figure 8; and

Fig. 10 is a side elevation diagrammatic in character illustrating the method of use of the device to aid escape from a vessel at sea.

The illustration of Figures 1 to 3 inclusive shows the device used in conjunction with a ladder. As shown the upper end of the ladder 10 has secured thereto a frame 11 having cross members 12 and 13 to define a rectangular opening in which the ring 14 which forms a rigid mouth for the chute 15 seats. As shown in Figure 4, the ring 14 is provided with an annular flange 16 to which the chute 15 is riveted.

The frame which is secured to the ladder also has hook portions 17 engageable over a sill 18 of the building and spacing lugs 19 to prevent the bearing of the chute against the building itself.

The chute 15 is made of material appropriate

to the use intended. If for use in connection with burning buildings, then the chute should be formed of non-inflammable material as woven asbestos. If the chute is to be used where it may be immersed in water, as at sea, it is preferably formed of waterproof material as rubber. A useful form of the invention is an asbestos exterior and rubber interior.

As clearly illustrated in Figures 1 and 9, the chute is of such a length that the lower end may approach the horizontal when in use, and to enable firemen, or others, to hold the chute in this position there are shown rigid bands 20 provided with handles 21 sufficient to accommodate enough men at each side (from one to four), to hold the device while a person or persons are sliding down its interior. The interior diameter of the chute is sufficient for ready passage of a person of any size.

Because the chute terminates as shown, the velocity of a person sliding through the same will be checked as he approaches the delivery end.

In its use as illustrated in Figure 5 without a ladder, the frame comprises horizontal members 22, 23 and cross members 12', 13'. The members 22, 23 are shown as terminating in hooks 24, 25 and supplementary members 26 underlie the members 22, 23, and are provided with downwardly projecting portions 27 spaced from the hook portions 24 a distance equal to the width of any usual windowsill. From the members 27 to the members 26 are shown braces 28 whereby the frame and the weight of the chute may be safely carried upon the sill of the building.

In the form of use of the invention of Figure 9 a device similar to Figures 5 and 6 is shown hooked over the rail of a vessel 29 and the delivery end of the chute is carried by a life-boat 30.

For convenience the boat is shown as formed with uprights 31 to which the delivery end of the chute may be secured as by the handles 21 in any suitable way. It is well known that one of the great hazards of escape from a vessel by its own lifeboats is in the swamping of the boats during launching, it being the usual practice for those who are to go in the boat to enter it before it is lowered from the davit. In the use of the present invention for this purpose the boat may be lowered with only a couple of men in it, desirably carrying the delivery end of the chute, and when afloat the lowering tackle may be cast off, leaving the boat moored to the vessel by the chute only. Women and children may be

fed into the chute, desirably feet first, and the men in the life-boat can receive them as delivered with great expedition and a minimum of hazard.

Under such conditions of escape, the vessel is normally used as a shield from the seas and the boat's mooring to the vessel by the chute will be down-wind from the vessel and therefore the drift of the boat will keep the chute sufficiently taut for its use. Should this strain upon the chute be insufficient, one man in the boat may ply the oars sufficiently to provide the necessary strain.

In the position of use shown in Figure 9 the stern of the lifeboat is toward the vessel, which position it may be desired to reverse.

Should one person seeking to escape by means of the device of the invention become stalled in the chute, so as to clog the passage of subsequent entries, a very serious condition would result.

To ensure that this does not happen by providing a positive feed of persons through the chute if used in a position not sufficiently near the vertical to ensure prompt passage by gravity alone, there is shown an endless flexible member 32 as a rope or flat, woven strip, having loop carrying members 33 attached thereto at intervals.

The loops may desirably be provided in the form of a usual "cattle-tie" comprising a snap hook 34 at the free end of each member 33 engageable with a ring 35 near the end of the member to form the loop. When not in use the snap hooks may each be in engagement with a ring 36 on the member 33 to prevent interference with bodies sliding in the chute.

Depending on the service required the chute may be made of any of the following materials:

Asbestos
Duck flameproofed
Tarpaulin flameproofed
Drill flameproofed
Canvas flameproofed
Rubberized asbestos
Rubberized duck flameproofed
Rubberized tarpaulin flameproofed
Rubberized canvas flameproofed
Rubberized drill flameproofed
Asbestos lined duck
Asbestos lined tarpaulin
Asbestos lined canvas
Asbestos lined drill

Minor changes may be made in the physical embodiment of the invention within the scope of the appended claims without departing from the spirit of the invention.

I claim:

1. A life saving device comprising, in combination: a tubular chute; a rim secured in an upper

end of the chute to hold the same open, comprising vertical and horizontal rigid members; a frame formed with vertical and horizontal members defining an opening receiving said rim, said frame also comprising a rigid member in spaced relation to said vertical members to span the upper edge of a structure to which the device is to be attached; substantially semi-circular rigid members secured to the upper portion of the lower end of the chute provided with means to be grasped to support the lower end of the chute in a position approaching the horizontal whereby to preserve flexibility of the lower portion of said lower open end for discharge of bodies sliding through the chute, without injury.

2. The combination of claim 1 with means to support said semi-circular rigid members upon a life-boat.

3. A life saving device comprising, in combination: a tubular chute; a rigid rim secured in an upper end of the chute to hold the same open; a rigid frame formed with vertical and horizontal members defining an opening receiving and supporting said rim; said frame also comprising a rigid member in spaced relation and rigid with said vertical members to span the upper edge of a structure to which the device is to be attached; a substantially semi-circular rigid member secured to the upper portion of the lower end of the chute provided with means to be engaged to support the lower end of the chute in a position approaching the horizontal whereby to preserve flexibility of the lower portion of said lower open end for discharge of bodies sliding through the chute, without injury.

4. A life saving device for marine use comprising, in combination: a flexible chute attached at one end to the rail of a vessel; a life boat attached to the remaining end of the chute; said chute forming essentially the sole connection between the vessel and the boat during use of the chute, whereby drift of the boat with propulsion thereof when needed may hold the chute extended away from the vessel side; and means whereby the chute-boat attaching means holds the discharge end of the chute open and over the interior of the boat.

5. A life saving device comprising, in combination: a tubular chute; means to attach an entrance end of the chute to a structure to be escaped from; a substantially semi-circular rigid member secured to the upper portion of the exit end of the chute; means carried by said rigid member to be engaged to support the lower end of the chute in a position approaching the horizontal whereby to preserve flexibility of the lower portion of said exit end and to hold the same open for discharge of bodies passing through the chute, without injury.

CHARLES HERENDEEN.
